G. A. DABNEY, OF SAN JOSÉ, CALIFORNIA.

Letters Patent No. 83,260, dated October 20, 1868.

IMPROVED WASHING-MACHINE.

The Schedule referred to in these Letters Patent and making part of the same.

To all whom it may concern:

Be it known that I, G. A. DABNEY, of San José, in the county of Santa Clara, and State of California, have invented a new and useful Improvement in Washing-Machines; and I do hereby declare that the following is a full, clear, and exact description thereof, which will enable those skilled in the art to make and use the same, reference being had to the accompanying drawings, forming part of this specification, in which—

Figure 1 is a vertical longitudinal section of my improved washing-machine.

Figure 2 is a detail view of the rubber.

Similar letters of reference indicate corresponding parts.

My invention has for its object to furnish an improved machine for washing clothes, which shall be simple in construction, and effective in operation, doing its work rapidly and thoroughly; and it consists in the construction and combination of various parts of the machine, as hereinafter more fully described.

A is the box or tub of the machine, which is made rectangular in its general form, with vertical sides and sloping ends, as shown in fig. 1, the end at which the operator stands being made higher than the other end, and the upper edges of the sides are curved downward, from the level of the higher end to the level of the lower end, as shown in fig. 1.

The box or tub A stands upon legs B and C, of such a length as to raise the said tub to a convenient height, and the bottom, at the end of the tub at which the operator stands, may be extended out to form a shelf, a', convenient for holding the soap.

The legs C, at the end of the tub farthest from the operator, are extended up above the upper edge of the tub to a sufficient height to support the swinging bars D, the upper ends of which are pivoted to the upper ends of the legs C by a round or rod, E, passing through the said upper ends of the said legs and the said upper ends of the said swinging bars.

To the lower ends of the swinging bars D are pivoted the rear ends of the side bars or levers F, to which the rubber-block G is pivoted.

The forward ends of the side bars F are connected

and held in their proper relative position by the rod or round H, which also forms a handle for operating the rubber.

The rubber-board or block G is pivoted at the centre of its ends to the side bars F, so that it may turn freely, and its opposite sides are grooved in a manner somewhat similar to the rubbing-surface of an ordinary wash-board.

One of the grooved sides of the rubber G may be covered with zinc or rubber, if desired, and in the grooves of the other side are secured bristles or other suitable fibrous material, the bunches of which are placed about half an inch apart, and cut off evenly about half an inch above the surface of said side.

I are two cross-bars connecting the side bars F, and which are placed, one at each edge of the rubber G.

J is a hook, one end of which is pivoted to one of the bars I, and which hooks into a staple attached to the other bar I, so as to lie along the upper side of the rubber G, holding it securely in position, and preventing it from revolving while being used, and, by unhooking which, the rubber may be adjusted, so that either side may be used as required.

K is a removable frame, placed in the bottom of the box or tub A, and to which is pivoted a series of rollers, L, the ends of which are pivoted to the frame K, and which should be arranged in a curve, corresponding with the movement of the rubber G.

If desired, the rollers L, or each alternate roller, may be replaced with grooved or brush-blocks, and in this case the rubber G should be made in the form of a series of rollers, but I prefer the construction first described, as operating more satisfactorily.

I claim as new, and desire to secure by Letters Patent—

The reversible rubber G, constructed as described, in combination with the side bars F, swing-bars D, and removable rubbing-platform K L, substantially as herein shown and described, and for the purpose set forth.

G. A. DABNEY.
